UNITED STATES PATENT OFFICE.

BRYANT W. CLAUSON, OF REXFORD, KANSAS.

ELECTRICAL DRAWER-LOCK.

1,265,054.

Specification of Letters Patent.

Patented May 7, 1918.

Application filed April 10, 1917. Serial No. 160,962.

To all whom it may concern:

Be it known that I, BRYANT W. CLAUSON, a citizen of the United States, and resident of Rexford, in the county of Thomas and State of Kansas, have invented certain new and useful Improvements in Electrical Drawer-Locks, of which the following is a specification.

This invention relates to furniture and has more particular reference to an improved drawer lock for desks and like articles.

The invention has for its dominant object to provide an electrically operated drawer lock whereby certain or all of the drawers of the desk can be automatically locked in their closed positions without the use of levers, spring catches or similar devices.

It is also an object of the invention to provide means for automatically moving the drawers to open positions, immediately subsequent to the unlocking of the same.

Other and further improvements and novel details in the construction and arrangement of parts will be appreciated from the description to follow, which for a clear understanding of the invention should be considered in connection with the accompanying drawings forming a part hereof and wherein the preferred embodiment of the invention is shown for the purpose of illustration.

In the drawings:

Figure 1 is a fragmentary vertical longitudinal section through a desk with my improved electrically operated lock applied thereto;

Fig. 2 is a fragmental end elevation thereof;

Fig. 3 is a detail in perspective of the electrically operated locking bolt;

Fig. 4 is a diagrammatic view showing the wiring of the electrically operated bolts; and

Fig. 5 is a detail in elevation of the improved circuit closing means for energizing the various electrically operated bolts.

Referring now more specifically to the several figures of the said drawings and in connection with which like reference characters will designate corresponding parts, there is shown a usual office desk indicated in its entirety by the numeral 1 and having arranged therein in proximity of the opposite sides of the same, a plurality of longitudinally disposed supporting bars design-

nated 2, the opposite extremities of which are engaged with similar transversely disposed bars 3, whereby the various drawers 4 of the desk will be slidably supported 60 therein. It is to be noted, in this connection that the drawers 4 are of a length slightly less than the length of the desk 1 and as a consequence, a chamber for receiving the electrically operated lock, which will 65 be subsequently described, is provided.

Upon the rear transversely disposed supporting bars 3, magnets 5 are secured through the medium of suitable straps or like connections, while to the opposite sides 70 of the drawer compartments of the said desk, apertured guide bars 6 are secured. Bolts 7 are slidably received through the openings formed in the guide bars 6 and carry upon their upper extremities armatures 8, adapted 75 to be attracted, at times, by the poles of their respective magnets 5. To the rear ends of each of the drawers 4, keepers 9 are affixed, as at 10 and are so positioned as to receive the lower extremities of the slideable bolt 7 80 therein. Contractile coiled springs 11 are secured to the lower faces of the rear end of the drawers 4 and the forward transversely supporting bars 3 of the desk and obviously, serve as means for automatically 85 moving the said drawers to open position immediately subsequent to the disengaging of the locking means therefrom.

In Fig. 4, there is shown a diagrammatic view of the method of wiring the various 90 magnets 5 whereby the same may be independently energized to actuate their respective armatures 8 and the slideable bolts 7 carried thereby. Main wires *a* are engaged with the opposite poles of a suitable 95 source of electrical energy *b*, one end of one of the wires being engaged with the contact point of a spring switch arm *c* while the other is engaged with a plurality or series of branch wires designated *d*. In these 100 branch wires *d*, the magnets 5 are interposed and the remaining or free extremities of the same are then extended into engagement with the various contact points *c'* of the circuit closing switch. It is to be noted, 105 that the switch arm is formed of spring metal and, as shown in Fig. 5 is normally maintained in spaced relation from the various contact points *c'*. Thus, when it is desired to close any one of the magnetic energizing circuits, the arm must be depressed in order that it will engage the de-

sired point. By this means, movement of the switch arm to the desired position previous to the closing of the selected magnet energizing circuit is permitted.

5 In operation, when it is desired to release certain of the slidable drawers 4, the proper magnets 5 are energized, thereby drawing the slidable locking bolts 7 together with the armature plates 8 into engagement there-
10 with. Obviously, upon disengagement of the bolt 7 from its respective keeper 9, the particular drawer as locked thereby will be instantly moved to open position due to the engagement of the contractile spring 11 therewith. The drawer may be readily closed, since, the locking bolt 7, due to its engagement with the electro-magnets 5 is out of the path of travel of the keeper 9. However, upon deenergization of the mag-
20 nets 5, the bolts will be again permitted to engage the pocket and as a consequence, securely lock the drawer in its closed position.

Manifestly, the construction shown is capable of considerable modification and such
25 modification as is within the scope of my claims, I consider within the spirit of my invention.

I claim:

1. The combination with an article of fur-
30 niture and the slidable drawers thereof, of a plurality of magnets supported adjacent

the rear portions of the drawer, apertured guide bars arranged in proximity of said magnets, slidable bolts received by the guide bars and having armature plates arranged 35 on their upper ends, keepers carried on the adjacent ends of said drawers for receiving the bolts therein, at times, means for independently energizing the magnets, and means engaged with the forward portions 40 of said article and the various drawers for imparting movement thereto subsequent to the releasing of the bolts.

2. The combination with an article of furniture and the slidable drawers thereof, 45 of a plurality of electro-magnets supported adjacent the rear portion of the article, apertured guide bars arranged in proximity of said electro-magnets, slidable bolts received by the guide bars and having armature plates arranged on their upper ends, keepers carried on the adjacent ends of said drawers for receiving the bolts therein, at times, means for independently energizing the electromagnets, and a plurality of contractile springs engaged with the forward portions of said article and the various drawers for moving the same to open position 55 subsequent to the releasing of the bolts.

In testimony whereof, I affix my signature hereto.

BRYANT W. CLAUSON.
